(57) **CLAIM**

We claim the ornamental Design for a disposable plate, as shown and described.

DESCRIPTION

FIG. 1 is a perspective view of a first embodiment of a disposable plate;

FIG. 2 is a top plan view of the plate of FIG. 1;

FIG. 3 is a front elevation view of the plate of FIG. 1, with an opposite view being identical thereto;

FIG. 4 is a side elevation view of the plate of FIG. 1, with an opposite view being identical thereto;

FIG. 5 is a bottom plan view of the plate of FIG. 1;

FIG. 6 is a top plan view of a second embodiment of the plate of the present invention, being a mirror-image of the plate of FIGS. 1–5;

FIG. 7 is a perspective view of a third embodiment of the plate of the present invention;

FIG. 8 is a top plan view of the plate of FIG. 7;

FIG. 9 is a front elevation view of the plate of FIG. 7, with an opposite view being identical thereto;

FIG. 10 is a side elevation view of the plate of FIG. 7, with an opposite view being identical thereto;

FIG. 11 is a bottom plan view of the plate of FIG. 7; and,

FIG. 12 is a top plan view of a fourth embodiment of the plate of the present invention, being a mirror-image of the plate of FIGS. 7–11.

Broken lines in the Figures form no part of the claimed design.
